HEAT VENTING ACCESSORY FOR A CLOTHES DRYER OR THE LIKE

Donald W. Grasmehr, Edison, Ohio, assignor to Whirlpool Corporation, a corporation of Delaware

Application September 19, 1956, Serial No. 43,004

Term of patent 14 years

(Cl. D49—1)

FIG. 1

FIG. 2

FIG. 3

FIG. 4

Figure 1 is a front perspective view of a heat venting accessory for a clothes dryer or the like embodying my new design;

Figure 2 is a side elevational view thereof;

Figure 3 is an enlarged top plan view of the heat venting accessory; and

Figure 4 is a front perspective view thereof on a reduced scale, the fragmentary top of a clothes dryer being for illustrative purposes only.

The dominant feature of the design is the accessory shown in perspective in Figure 1 and in elevation in Figure 2.

I claim:

The ornamental design for a heat venting accessory for a clothes dryer or the like, as shown and described.
